Primary Examiner — T Chase Nelson*Assistant Examiner* — Kelly L Gross(74) *Attorney, Agent, or Firm* — McDonnell Boehnen Hulbert & Berghoff LLP(57) **CLAIM**

The ornamental design for a cryotherapy device, as shown and described.

DESCRIPTION

FIG. 1 is a perspective view of a cryotherapy device of the present design;

FIG. 2 is a right side view thereof;

FIG. 3 is a left side view thereof;

FIG. 4 is a rear view thereof;

FIG. 5 is a front view thereof;

FIG. 6 is top view thereof; and,

FIG. 7 is bottom view thereof.

The portions of the drawings shown in broken lines represent environmental structure and form no part of the claimed design. The parallel, wavy lines shown in broken lines are symbolic breaks, and any portion of the cryotherapy device between the breakaways forms no part of the claimed design.

1 Claim, 6 Drawing Sheets(56)
